UNITED STATES PATENT OFFICE.

CHARLES OLSON, OF GRAND RAPIDS, MICHIGAN.

STEAM-BOILER.

SPECIFICATION forming part of Letters Patent No. 728,284, dated May 19, 1903.

Application filed September 19, 1902. Serial No. 124,119. (No model.)

To all whom it may concern:-

Be it known that I, CHARLES OLSON, a citizen of the United States, residing at Grand Rapids, in the county of Kent and State of Michigan, have invented certain new and useful Improvements in Steam-Boilers; and I do hereby declare the following to be a full, clear, and exact description of the invention, such as will enable others skilled in the art to which it appertains to make and use the same.

My invention relates to improvements in steam-boilers, and more especially to improvements in the style of boilers shown in my application, Serial No. 100,041, filed March 26, 1902; and the object of my present invention is to increase the amount of heating-surface in a boiler of a given size and to provide the same with certain new and useful features, hereinafter more fully described, and particularly pointed out in the claims, reference being had to the accompanying drawings, in which—

Figure 1 is a side elevation of a device embodying my invention with a portion of the outer shell broken away to show the construction; Fig. 2, a vertical section of the same on the line 2 2 of Figs. 1 and 3 with the curved tubes omitted; Fig. 3, an inverted plan of the lower end of the same, and Fig. 4 a plan of the upper end of the same.

Like letters refer to like parts in all of the figures.

A represents the outer shell of the boiler, tubular in form and having detachable rings B at each end projecting inward and provided with a series of set-screws C.

J is the packing, and K the packing-ring, the device so far being the same as shown in my aforesaid application.

D is an inner tubular shell of sufficiently less diameter than the outer shell A to leave a suitable water-space between and provided at each end with outwardly-projecting flanges D', engaging the inner surface of the shell A and the packing J, thus forming an annular chamber between the two shells A and D. This inner shell D is open at the bottom and provided with a head H, closing the upper end of both shells, and a crown-sheet G, located a little below the water-line and parallel to the head H. The space between the head H and crown-sheet G constitutes the steam-

space of the boiler, and openings E are formed in the inner shell D to permit free circulation of the steam and water between the steam-space and the annular space between the two shells.

I represents any suitable number of flues extending vertically through the head H and crown-sheet G.

The interior of the inner shell D below the crown-sheet constitutes the fire-box and heating-chamber, and within this space are located the inwardly-projecting curved tubes F, inserted in the shell D and opening at each end into the space between it and the outer shell A. These tubes are each preferably bent in a regular curve, forming a segment of such length and radius as to engage the side of the inner shell at substantially right angles where inserted therein, and they are formed of different lengths and radii, whereby two or more may be arranged near each other and concentric and also in the same plane. Each tube is preferably arranged in a horizontal position in the fire-box, and said tubes are also in superposed planes and in ascending spirals, thus being laterally presented to the ascending currents of hot gases from the fire and imparting a spiral motion thereto to more effectually circulate the same among the tubes and more effectually heat the same.

The device is intended more especially for use in small boilers, and particularly in boilers operated by gasoline or other liquid-fuel burners, and is particularly intended for automobile-boilers.

The operation will be readily understood from the foregoing description without further explanation.

Having thus fully described my invention, what I claim, and desire to secure by Letters Patent, is—

1. In a steam-boiler, a double shell with a water-space surrounding the fire-box, and tubes bent in arcs of circles and arranged in horizontal planes within the fire-box; each tube having both ends opening through the side of the fire-box and into the water-space.

2. In a steam-boiler, an inner shell forming the wall of the fire-box, an outer shell surrounding the inner shell and detachably connected thereto, and tubes bent in arcs of circles and arranged in horizontal planes

within the fire-box each tube having both ends inserted in the wall of the fire-box and in the same horizontal plane.

3. In a steam-boiler, a double shell with 5 water-space, and surrounding the fire-box, tubes bent in arcs of circles and having different lengths and radii and concentrically arranged in the same horizontal plane within the fire-box each tube also having both of its 10 ends inserted in the wall of the fire-box and opening into the water-space surrounding the same.

4. In a steam-boiler, an inner shell forming the wall of the fire-box, an outer shell 15 surrounding the inner shell detachably connected thereto, and having a water-space between, tubes bent in arcs of circles, and inserted in the inner shell, said tubes being arranged in horizontal planes within the fire- 20 box and in spiral series vertically.

5. The combination of an inner and an outer shell having an annular space between them, lateral openings in the upper part of

the inner shell, a head closing the upper ends of the shell, a crown-sheet at a distance below 25 the head and parallel therewith, flues connecting the head and crown-sheet, and tubes inserted in the inner shell and extending horizontally inward therefrom and opening at both ends into the space between the shells. 30

6. The combination of an inner and outer shell with space between, a crown-sheet in the inner shell, an upper head closing the outer shell, flues extending through the crown-sheet and head, and tubes inserted in the inner shell and extending inward therefrom and opening into the space between the shells at both ends, said tubes also being bent in arcs of circles and arranged in horizontal planes and spirally in vertical series. 40

In testimony whereof I affix my signature in presence of two witnesses.

CHARLES OLSON.
